UNITED STATES PATENT OFFICE

JOHN F. SCHWEIGER, OF FLORA, INDIANA

FOUNTAIN PEN

Application filed April 20, 1929. Serial No. 356,657.

The present invention relates to improvements in fountain pens and the primary object of the invention is to provide an improved construction for fountain pens embodying ink feeding means for insuring an even flow of ink to the pen point regardless of the quantity of ink in the ink container of the pen.

A further object of the invention is to provide a fountain pen wherein a barometric feed principle is employed for maintaining an even feeding of the ink regardless of the quantity of ink in the ink container of the pen.

15 A further and important object of the invention is to provide means whereby the ink will be instantaneously fed to the pen point thru capillary movement when the pen is placed in a writing position.

20 A still further and important object is to facilitate greater convenience and more practical utility in the general adaptability of fountain pens by providing the same with a removable non-collapsible ink container of 25 rigid material such as glass, and which containers are readily insertable into the barrel of the fountain pen as required from time to time and eliminates the numerous troubles incident to use of the collapsible rubber ink 30 sacks which deteriorate and contaminate the ink and require frequent filling since the same cannot be filled to full capacity.

Other objects and advantages of the invention will be apparent during the course 35 of the following detailed description, taken in connection with the accompanying drawings forming a part of this specification and in which drawings:

Figure 1 is a central longitudinal section 40 thru the improved fountain pen.

Figure 2 is a view showing the ink container applied to the pen stock ready for insertion into the pen barrel.

45 Figure 3 is an elevation of the refill ink container and showing the cap in position for closing the mouth of the container prior to use.

Figure 4 is an enlarged fragmentary longitudinal section on the line 4-4 of Figure 1.

Figure 5 is a transverse section on line 5-5 of Figure 4.

In the drawings, and wherein similar reference characters designate corresponding parts thruout the several views, the numeral 55 6 designates the barrel of the pen preferably of cylindrical formation being closed at its rear end and having its front open end provided with external screw threads 7 for threaded reception of the cap 8 which may 60 be slipped over the rear tapering portion of the barrel. The cap 8 serves as a protection for the writing end of the pen when turned on the thread 7.

Removably and preferably slidably fitting in the forward open end of the barrel 6 is a pen stock 9 embodying a tubular sleeve portion 10 preferably provided intermediate its ends with an external shoulder 11 which abuts with the forward end of the barrel 6 70 for limiting movement of the pen stock into the forward open end of the barrel. Fitting within and closing the forward portion of the sleeve 10 is a cylindrical head portion 12 of a feed bar 13 provided at its forward end with any suitable form of distributor 14 engaging the concaved side of the pen point 15.

75 The feed bar head portion 12 is of special formation and has its flat inner end counter-bored to provide a relatively shallow cavity 15 having a flat bottom surface and an overhanging circumferential flange 16 providing an undercut cavity at the inner end of the head portion. The flange 16 is 80 provided with a way 17 which communicates with a feed duct 18 formed longitudinally in the external surface of the head 12 and communicating with the distributor 14 for feeding ink to the pen point 15.

85 The ink container 20 is preferably formed from glass or other suitable material and preferably constitutes the vessel in which the ink may be vended. The container is provided with a reduced neck portion 21 and prior to use of the container the neck is 90 preferably closed by means of a suitable closure cap 22 fitting externally over the open end of the neck. The closure cap 22 extends 95 for a substantial distance over the open end 100

of the container and is preferably provided with a knob for enabling ready and easy removal of the cap from the container when applying the container to the pen stock.

5 The open end of the neck 21 is provided with a suitable number of V-shaped notches 24 forming ink control passages when the container is applied to the pen stock.

Fitting within the rear portion of the 10 tubular sleeve portion 10 is a suitable gasket

25 having an axial opening therethru for slidably and snugly receiving the reduced neck portion 21 of the ink container 20 for supporting the ink container co-axial with 15 the pen stock within the barrel 6. When replacing the ink container, the pen stock is withdrawn from the barrel 6 and the full container of ink attached to the pen stock by inserting the neck 21 thru the opening

20 in the gasket 25 until the straight end of the neck abuts with the flat bottom surface of the undercut cavity 15 as clearly shown in Figure 4. After the full ink container is applied to the pen stock as shown in Figure 2, the assembly is then inserted into the barrel 6 and the fountain pen made ready for use.

When the pen is turned into a writing position, ink from the container will flow thru 30 the openings formed by the notches 24 into the cavity 15, filling the same and then having passage thru the way 17 into the feed duct 18 for ready passage to the distributor for the pen point 15'. After the cavity 15 becomes filled it will be seen that further 35 feeding of the ink from the container will be thru barometric action and thus maintain an even feeding of the ink regardless of the quantity of ink in the ink container.

40 When the pen is not being used and with the pen point up, a portion of the ink recedes back into the ink container 20, except for a small quantity of ink which remains in the pocket formed between the head 12 and gasket 25 and thus no ink is left in the feed duct 18 for thickening and hardening 45 beneath and about the pen point. The partial vacuum created by the barometric feed action tends to fully withdraw all ink from the feed duct 18. The ink however remaining in the cavity 15 keeps the walls thereof wet with ink so that immediately upon placing of the pen in a writing position quick movement of the ink to the pen point 50 is insured thru capillary action owing to the fact that the walls of the cavity 15 are wet from the ink and thus allows ready movement of the ink to the feed duct 18. Thus it will be seen that when the pen is 55 not in use with the pen point up, that the ink is withdrawn from the pen point and that when the pen is in a writing position with the pen point down that quick flow of ink to the pen point is insured.

60 While the spacing between the inner end

of the head portion 12 and gasket 25 may be varied, it has been found in use that this spacing is governed by the size of the fountain pen in which the improved feed method is employed. In the larger size of fountain pens the gasket may be disposed in contact with the inner end of the head 12, while in smaller size fountain pens and for providing a larger pocket, the gasket should be spaced from the head 12.

70 With the novel arrangement shown employing a rigid ink container formed of glass or similar material, the ink may be vended in the containers and when placed in the pen, the refill will be the maximum amount of ink which may be contained in the pen at one time and yet this maximum quantity of ink will have no tendency to feed ink too freely to the pen point.

75 From the foregoing it will be apparent that an improved construction for fountain pens has been disclosed embodying features whereby full ink capacity of the pen is had by mere replacing of filled containers preferably forming the vessels in which the ink is vended, and which pen employs a barometric feed principle for maintaining an even feed of the ink regardless of the quantity of ink in the container. It will also be apparent that a novel arrangement has 80 been disclosed wherein quick feeding of the ink to the pen point is insured when the pen is inverted for use.

Changes in detail may be made to the form 85 of invention herein shown and described, without departing from the spirit of the invention or the scope of the following claims.

I claim:

1. A fountain pen comprising a barrel, a pen stock removably fitting in one end of the barrel and having an ink pocket and a feed duct communicating with the pocket, and a noncollapsible ink container supported at one end in the pen stock with its open end extending into said pocket into abutting engagement with one wall thereof, said open end of the container being notched in its side to provide communication between the container and ink pocket.

105 110 115 120 125 130

2. In a fountain pen, a barrel, a pen stock removably insertable into one end of the barrel including a head portion having a cavity at its inner end and a feed duct communicating with the cavity, and an ink container supported by the inner end of the pen stock with its open end seating upon the base surface of the cavity, said open end of the container being notched to provide communicating openings from the container into the cavity.

3. In a fountain pen, a barrel, a pen stock removably fitting in one end of the barrel including a head portion having a counter-bored cavity at its inner end provided with a

flat bottom surface and a feed duct communicating with a cavity, a gasket inwardly of the cavity, and an ink container supported at one end in the gasket with its open end seated upon the flat bottom surface of the cavity and having a notched end edge.

4. In a fountain pen, a barrel, a pen stock removably fitting in one end of the barrel including a feed bar embodying a head portion having a counter-bore at its inner end forming an undercut cavity having a flat bottom surface and an overhanging circumferential flange, the flange having an opening communicating with the inner end of a feed duct, a gasket arranged in the pen stock inwardly of the undercut cavity, and a rigid ink container having a notched open end, removably insertable thru the gasket with the edge of its open end seating upon the flat bottom surface of the cavity.

5. In a fountain pen, a barrel, a removable pen stock including a tubular sleeve portion for limited insertion into one end of the barrel, a feed bar including a head portion fitting in the outer end of the sleeve and having an undercut cavity at its inner end provided with a flat bottom surface and a feed passageway opening into the cavity, a gasket arranged in the inner end of the sleeve forming a closed pocket at the inner end of the feed bar, and a non-collapsible ink container having a straight cut open end insertable thru the gasket into seating relation upon the flat bottom surface of the cavity, said container being notched at its open end edge.

6. In a fountain pen, a barrel, a removable pen stock including a tubular sleeve portion for limited insertion into one end of the barrel, a feed bar including a head portion fitting in the outer end of the sleeve and having an undercut cavity at its inner end provided with a flat bottom surface and a feed passageway opening into the cavity, a tubular gasket removably insertable into the inner end of the sleeve over the cavity, and a rigid ink container having a straight cut open end insertable thru the gasket into seating relation upon the flat bottom surface of the cavity, said container being notched at its open end edge.

JOHN F. SCHWEIGER.
